(57) CLAIM

The ornamental design for an ankle ice pack, as shown and described.

DESCRIPTION

FIG. 1 is a front, right side, top perspective view of an ankle ice pack showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, right side, top perspective view thereof when being secured around the ankle area of a foot.

The broken lines shown in the drawings illustrate portions of the ankle ice pack that form no part of the claimed design. In FIG. 9, the broken lines showing a foot depict environment and form no part of the claimed design.
